UNITED STATES PATENT OFFICE.

ALONZO SEDGWICK, OF POUGHKEEPSIE, ASSIGNOR, BY MESNE ASSIGNMENTS,
TO D. H. BURRELL & CO., OF LITTLE FALLS, NEW YORK.

RULING-MACHINE.

SPECIFICATION forming part of Letters Patent No. 441,905, dated December 2, 1890.

Application filed June 2, 1887. Serial No. 240,054. (No model.)

To all whom it may concern:

Be it known that I, ALONZO SEDGWICK, of the city of Poughkeepsie, in the county of Dutchess and State of New York, have invented new and useful Improvements in Ruling-Machines, of which the following is a specification.

This invention relates to that class of ruling-machines in which the lines are formed upon the paper by means of thin disks or rings, to the edges of which the ink is applied. The lines produced by such machines are frequently broken or imperfect, especially when it is attempted to produce fine lines.

The object of my invention is to overcome this difficulty; and it consists of the improvements which will be hereinafter fully described, and pointed out in the claims.

In the accompanying drawings, consisting of two sheets, Figure 1 is a longitudinal sectional elevation of a ruling-machine provided with my improvements. Fig. 2 is a top plan view of the same. Fig. 3 is a side elevation thereof. Figs. 4 and 5 are fragmentary sectional elevations, the sections being taken in lines *x x* and *y y*, Fig. 1. Fig. 6 is a fragmentary longitudinal section, and Fig. 7 a cross-section showing a modified construction of one of the supporting-rollers on an enlarged scale. Fig. 8 is an elevation showing a modified construction of the inking mechanism.

Like letters of reference refer to like parts in the several figures.

A' represent the side frames of the machine, and *a* the horizontal main shaft journaled in the same.

B represents the feed-tapes by which the paper is supplied to the machine, and which run around a tape-roller *b*, journaled in the side frames A A'.

b' is a pressure-roller resting on the tapes above the tape-roller *b*.

C represents the lower ruling-cylinder, provided with a series of thin ruling-rings *c*, which are secured side by side to the surface of the cylinder in any suitable manner.

D represents the ink-fountain, from which ink is supplied to the rings *c* by an inking-roller *E* and an intermediate roller *E'*. The ink-roller *E* is provided on its face with rings

e, which correspond in arrangement with the ruling-rings *c* on the cylinder C, but are somewhat wider in their faces. These rings *e* elevate the ink from the fountain to the intermediate roller *E'* and the latter transfers the ink to the ruling-rings *c*. The spaces between the rings *e* permit the excess of the elevated ink to flow back into the fountain on the descending side of the ink-roller and prevent the intermediate roller and the ruling-rings from becoming flooded. A similar result is obtained by providing the intermediate roller *E'* with inking-rings and constructing the ink-roller *E* with a plain face, as represented in Fig. 8.

F represents the supporting or pressure roller, which is arranged above the ruling-cylinder C, and on which the paper finds a support in passing over the ruling-rings. The roller F is provided with a flexible or yielding surface, which adapts itself to the inequalities of the paper and enables a smooth and uniform impression to be produced. As shown in Fig. 1, the supporting-roller consists of a rigid core *f* of metal or other suitable material and a covering or outer jacket *f'* of soft rubber. It may, however, be constructed in the form of a cylindrical brush *f''*, as represented in Figs. 6 and 7. In this case the bristles *f'''* may be clamped between collars *f''*, applied to the face of the roller.

G represents the upper ruling-cylinder, constructed like the lower cylinder C.

H represents the lower supporting-roller, constructed like the upper supporting-roller F; I, the ink-fountain; J, the ink-roller, arranged in the same, and J' the intermediate roller interposed between the roller J and the ruling-cylinder G.

In the drawings each of the ruling-cylinders, supporting-rollers, inking and intermediate rollers is shown as composed of two sections arranged side by side upon the same shaft; but said cylinders or rollers may be provided with a single face or more numerous faces, as the desired style of ruling may require.

K represents the receiving-table, to which the sheets are delivered from the last ruling-cylinder G.

L represents a gear-wheel, secured to the main shaft *a* on the outer side of the side frame A.

l is a gear-wheel secured to the shaft of the lower ruling-cylinder C and meshing with the wheel L.

l' is a gear-wheel secured to the shaft of the upper supporting-roller F and meshing with the wheel *l*; *m*, a gear-wheel secured to the shaft of the lower supporting-roller H and meshing with the wheel L, and *m'* a gear-wheel secured to the shaft of the upper ruling-cylinder G and meshing with the wheel *m*.

The wheels *l* and *m'* are of equal size and 15 larger in diameter than the wheels *l'* and *m*, so that the supporting-rollers revolve with a greater peripheral speed than the ruling-rings. As the supporting-rollers have a much larger surface in contact with the paper than the 20 ruling-rings, the speed with which the paper moves past the ruling-rings is controlled by the peripheral speed of the supporting-rollers, so that under the above-described proportions of the gear-wheels, the paper 25 moves past the ruling-rings with a speed greater than the peripheral speed of these rings. This differential speed produces a drawing action of the ruling-rings on the paper similar to the action of drawing a pen 30 over paper and causes an equalization of the action of the rings on the paper, whereby breaks or imperfections in the lines are prevented. This permits very thin ruling-rings to be used and enables the machine to produce fine lines of even appearance. A similar effect is produced by causing the paper 35 to move slower than the peripheral speed of the ruling-rings.

n represents a guide, which is arranged in 40 advance of the ruling-cylinder C, and which directs the paper against the same out of a tangential line, so as to impinge against the ruling-rings thereof before the paper reaches the supporting-roller. This guide causes the 45 paper to be wrapped around that part of the ruling-cylinder which lies between the guide *n* and the supporting-roller F, as indicated by dotted lines in Fig. 1. A longer contact of the paper with the ruling-rings is thus secured, whereby an additional safeguard is 50

obtained against breaks or imperfections in the lines. A similar guide *n'* is arranged in front of the second ruling-cylinder G. The guide *n* may be composed of a transverse rod and the guide *n'* of a transverse plate, as 55 shown in Fig. 1. These guides avoid the necessity of placing the supporting-rollers in close contact with the inking-rings, so that the fine relative adjustment of these parts which was heretofore required is dispensed 60 with.

By my improvements perfect lines can be produced with such a small quantity of ink that the sheets can be delivered directly from the ruling mechanism upon the receiving-table without the interposition of carrying-tapes or other mechanism for drying or delivering the same. 65

I claim as my invention—

1. The combination, with a ruling-cylinder 70 provided with ruling-rings, of a supporting-roller and differential driving-gear connected with the ruling-cylinder and the supporting-roller, whereby these parts are driven with differential peripheral speed, substantially as 75 set forth.

2. The combination, with the ruling-cylinder and the supporting-cylinder, of a guide whereby the paper is deflected out of its tangential course and caused to be wrapped 80 around the ruling-cylinder, substantially as set forth.

3. The combination, with the ruling-cylinder, of a supporting-cylinder having its face composed of a cylindrical brush, substantially as set forth. 85

4. The combination, with the ruling-cylinder provided with ruling-rings, of an ink-fountain, an inking-roller provided on its face with projecting rings, and an intermediate roller interposed between the inking-roller and the ruling-cylinder, substantially as set forth. 90

Witness my hand this 26th day of May, 1887.

ALONZO SEDGWICK.
